Vernon, N. Y., and one-third to Robert J. Earl,
New York, N. Y.

Application June 22, 1935, Serial No. 27,845

11 Claims. (Cl. 72—126)

This invention relates to a dampproof wall structure in general and particularly to flooring and also to the method of constructing the dampproof structure of the wall or the dampproof structure of the flooring made according to the present invention.

Among the objects of the present invention, it is aimed to provide an improved dampproof wall structure and particularly a dampproof flooring in which there is interposed between the sub-wall or flooring structure and the main wall or flooring structure an uninterrupted continuous layer of non-corrosive and dampproof metal and binding the three together consisting essentially 15 in a sub-structure composed as an instance of concrete, a main wall or flooring composed as an instance of wood, rubber, linoleum, cork or the like and strips of a dampproof metal such as sheet copper of about .0027 inch gauge bonded 20 together by dampproof uninterrupted sweated joints with the sheet metal bonded to the sub-structure by a water-proof adhesive, such as asphalt and after the joints of the metal strips have been sealed, then the main wall structure 25 or flooring, such as wood, rubber, linoleum, cork or the like bonded to this sheet metal layer by an adhesive, such as asphalt cement or the like.

It is still another object of the present invention to provide a method for constructing the 30 dampproof structure of a wall or flooring made according to the present invention which consists in spreading an adhesive such as asphalt upon the subwall structure or flooring, then laying the sheet metal strips with the adjacent edge 35 of each succeeding strip overlapping an inch or more of the preceding sheet metal strip so that such overlapping portions are free from asphalt and form pockets into which there are then inserted continuous strips of sealing compound and 40 thereupon the heat applied to the outer face of the overlapping flanges and a cooling medium applied immediately thereafter so that the sweated bond between the sheets may be effectively sealed with a minimum amount of labor and at a 45 minimum cost.

These and other features, capabilities and advantages will appear from the subjoined detail description of specific embodiments of the wall structure and the method of constructing the 50 wall structure illustrated in the accompanying drawing in which

Figure 1 is a cross section of a wall structure or flooring made according to the present invention;

Fig. 2 is a cross section of a combined wall

structure and flooring made according to the present invention;

Fig. 3 is a fragmental cross section of another embodiment of wall structure or flooring made according to the present invention;

Fig. 4 is a perspective view illustrating one method of constructing the dampproof structure of a wall or flooring made according to the present invention; and

Fig. 5 is a perspective view illustrating another 10 method of constructing the dampproof structure of a wall or flooring made according to the present invention.

In the embodiment shown in Fig. 1, there is provided a sub-wall or flooring structure 1 composed of concrete or the like, a main wall structure or flooring structure 2 composed of wood, rubber, linoleum, cork or the like and an intervening dampproof sheet metal layer 3 composed of a plurality of thin non-corrosive moisture or 20 dampproof metal strips, such as copper sheets of about .0027 inch gauge by thirty inches wide, the overlapping longitudinally extending edges of which are bonded together by an uninterrupted continuous dampproof sweating joint or 25 seal.

The sheet metal layer 3 is preferably bonded to the subwall structure 1 by a waterproof adhesive, such as an asphalt layer 4 and the main wall structure 2 is preferably bonded to the sheet 30 metal layer 3 by an adhesive, such as the asphalt cement layer 5 or the like depending upon the character of the main wall structure. As an instance, if the main wall structure 2 is composed of wood, a mastic binding is used; if composed of 35 rubber or cork a rubber cement is used and if composed of linoleum then a linoleum paste is used.

The wall structure constructed according to Fig. 2 consists in a subwall structure 6 composed 40 of concrete and embraces the flooring structure 7 and vertically extending wall structures 8 and 9. In this embodiment, the waterproof adhesive, such as asphalt is first brushed or spread over the upper surface of the flooring structure 7 and the 45 inner faces of the wall structures 8 and 9 and then the strips 10 of sheet metal laid onto such adhesive, whereupon it will immediately adhere to the flooring structure 7 and wall structures 8 and 9. When so laying the sheet metal strips 10, 50 the longitudinal edge of each succeeding metal strip preferably overlaps a longitudinal edge of a preceding strip so as to form a flange or border of a succeeding strip of about one and a half inches in width overlapping the flange or border 55

of a preceding strip of about one and a half inches in width. After the strips 10 are so laid and adhered to the substructures 7, 8 and 9, the overlapping flange will form a pocket. The 5 pocket so formed constitutes an important part of the present invention.

In this pocket an uninterrupted continuous length of round sealing wire or flat sealing ribbon is placed, the pocket formed by the overlapping 10 flanges facilitating the rapid location of the wire 11 without the use of any measuring instruments or any position defining devices. Thereupon, it will only be necessary to apply heat to the outer 15 face of the flange of a succeeding strip 10 as an instance by passing an ordinary sadiron 12 across the same. Preferably so that the joint may be cooled and thereafter sealed as quickly as possible, a cooling roller, such as the roller 13 may be passed across the outer face of the overlapping flange immediately following the sadiron 14.

In the embodiment shown in Fig. 5, instead of the round sealing wire 11, there is used a flat sealing ribbon 14 which cooperates still better with the pocket formed by the overlapping flanges of adjacent strips 10 to maintain its position before and during the sweating operation.

In this embodiment also instead of the sadiron a gasoline torch 15 is used to apply heat to the 30 overlapping flanges and this torch 15 followed by a cooling roller 16.

In the embodiment illustrated in Fig. 3, the metal strip 17 along the corner of a room between the floor substructure 18 and the side wall sub- 35 structure 19 is bent back over the main flooring 20 to form a U-shaped end and thereby seal the edge of the flooring adjacent the wall structure 19 and also extends up at 21 along the inner face of the wall structure 19 above the main flooring 40 20 to any desired height.

The sealing wire 11 and sealing ribbon 14 are preferably acid filled, each consisting of a shell composed of tin and lead enclosing an acid filler.

With the present invention, it will be seen that 45 an effective uninterrupted continuous waterproof layer will be interposed between the subwall structure and the main wall structure or between the subflooring structure and main flooring structure, which will find especial utility with a room constructed below grade to prevent the admission of ground moisture. When the waterproof layer is composed of thin sheet copper, there will be provided a layer which will be immune to attack 50 from moisture as well as prevent the passage of moisture therethrough to the main flooring and in addition there will be formed an effective lining or layer for preventing the passage of vermin, termites, and rodents by way of the wall structure or floor structure so equipped.

60 It is obvious that various changes and modifications may be made in the structure and in the steps of the method aforesaid without departing from the general spirit of the invention set forth 65 in the appended claims.

I claim:

1. A dampproof wall structure embracing a 70 subwall structure, a main interior wall structure, and an intervening continuous dampproof metal layer composed of strips of metal immune to corrosion from moisture, said metal strips having dampproof sweated joints for securing the same to one another.

2. A dampproof wall structure embracing a 75 subwall structure, a main interior wall structure,

an intervening continuous dampproof metal layer composed of strips of metal immune to corrosion from moisture, a dampproof bonding medium for securing said metal layer to said subwall structure, a second bonding medium for securing said 5 interior wall structure to said metal layer, and a sweated joint for bonding adjacent overlapping flanges of said strips to one another.

3. A dampproof wall structure embracing a 10 subwall structure composed of concrete, a main interior wall structure composed of wood, an intervening continuous dampproof copper layer composed of strips of copper immune to corrosion from moisture, a dampproof asphalt adhesive for securing said copper layer to said subwall 15 structure, an adhesive cement for securing said interior wall structure to said copper layer, and a sweated joint for bonding adjacent overlapping flanges of said copper strips to one another.

4. A dampproof flooring embracing a concrete 20 sub-structure, a main flooring composed of wood, an intervening continuous dampproof metal layer composed of strips of copper immune to corrosion from moisture, and adhesive for securing said metal layer to said sub-structure and for securing 25 said main flooring to said metal layer, said metal strips having dampproof sweated joints for securing the same to one another.

5. A dampproof flooring embracing a concrete 30 sub-structure, a main flooring composed of rubber, an intervening continuous dampproof layer composed of strips of sheet copper immune to corrosion from moisture, a dampproof asphalt adhesive for securing said copper strips to said 35 sub-structure, a rubber cement for securing said rubber flooring to said copper strips, and a sweat- ed joint for bonding adjacent overlapping flanges of said strips to one another.

6. A dampproof flooring embracing a concrete 40 sub-structure, a main flooring composed of rubber, an intervening continuous dampproof layer composed of strips of sheet copper immune to corrosion from moisture, a dampproof asphalt adhesive for securing said copper strips to said 45 sub-structure, a rubber cement for securing said rubber flooring to said copper strips, and a sweat- ed joint for bonding adjacent overlapping flanges of said strips to one another, said sweat- ed joint being composed of tin, lead and acid.

7. A dampproof flooring embracing a sub- 50 structure, a main flooring composed of cork, an intervening continuous dampproof layer composed of strips of sheet copper immune to corrosion from moisture, a dampproof asphalt adhesive for securing said copper strips to said sub- 55 structure, a rubber cement for securing said cork flooring to said copper strips, and a sweat- ed joint for bonding adjacent overlapping flanges of said strips to one another.

8. A dampproof flooring embracing a sub- 60 structure, a main flooring composed of linoleum, an intervening continuous dampproof layer composed of strips of sheet copper immune to corrosion from moisture, a dampproof asphalt adhesive for securing said copper strips to said sub- 65 structure, a linoleum paste for securing said linoleum flooring to said copper strips, and a sweat- ed joint for bonding adjacent overlapping flanges of said strips to one another.

9. A dampproof flooring embracing a sub- 70 structure, a main flooring, an intervening con- 75 tinuous dampproof metal layer composed of strips of sheet copper immune to corrosion from moisture, and a sweat- ed joint for bonding adjacent overlapping flanges of said strips to one another.

said metal layer being bent around the edges of the main flooring to seal the same.

10. The method of constructing a dampproof structure consisting in spreading an asphalt adhesive upon a sub-structure, thereupon laying a plurality of metal strips upon said adhesive with a longitudinal flange of a succeeding strip overlapping a longitudinal flange of a preceding strip to form a pocket, inserting a continuous sealing strip in said pocket, thereupon applying heat and pressure to the outer face of the succeeding flange, subsequently cooling said succeeding flange, and thereupon adhesively securing the

main outer wall structure to said metal strips so joined.

11. The method of forming a dampproof flooring consisting in adhesively securing a plurality of metal strips upon a sub-structure with the flange of a succeeding strip overlapping the flange of a preceding strip to form a pocket, thereupon inserting a continuous sealing strip in said pocket, thereupon applying heat and pressure to the succeeding flange, thereupon cooling said flange, and thereupon adhesively securing the main flooring to said metal strips so joined. 5

NOËL L. DAHLANDER.
